Primary Examiner — Austin Murphy(74) Attorney, Agent, or Firm — Foley & Lardner LLP(57) CLAIM

I claim the ornamental design for a dish mat, as shown and described.

DESCRIPTION

FIG. 1 is a perspective view of an embodiment of the claimed design;

FIG. 2 is a front view of the embodiment of FIG. 1;

FIG. 3 is a top view of the embodiment of FIG. 1; and,

FIG. 4 is a side view of the embodiment of FIG. 1.

The ornamental design which is claimed is shown in solid lines in the drawings.

1 Claim, 3 Drawing Sheets(56)
